GIOVANNI EMANUELE ELIA, OF ROME, ITALY

FIRING APPARATUS FOR MOORED TORPEDOES.

1,092,703.

Specification of Letters Patent.

Patented Apr. 7, 1914.

Application filed July 5, 1913. Serial No. 777,460.

To all whom it may concern:

Be it known that I, GIOVANNI EMANUELE ELIA, a subject of the King of Italy, and a resident of Rome, Italy, have invented a new and Improved Firing Apparatus for Moored Torpedoes, of which the following is a full, clear, and exact description.

This invention relates to a firing apparatus especially adapted for moored torpedoes or mines of the spherical or cylindrical type, and the firing mechanism relies for its actuation upon the well known fact that a spherical or cylindrical torpedo acquires rotative motion from a vessel coming into contact therewith.

The invention has for its general objects to provide a reliable and effective firing apparatus of the type referred to which is comparatively simple and inexpensive to manufacture and so designed as to provide for a maximum degree of safety in the handling of the torpedo as in mooring it in or removing it from the water.

A further object of the invention is the provision of a firing mechanism that includes an inertia or resistance device which tends to maintain its position when the torpedo or mine is rotated by contact with the vessel, so that this relative movement between the device and torpedo causes a firing pin or hammer to be released, whereby the charge of the torpedo is exploded.

Another object of the invention is the provision of a novel and effective locking means whereby relative movement of the said inertia device and body of the torpedo is prevented as long as the torpedo is not moored or anchored.

A further object of the invention is the provision of a torpedo having a cap and fuse for the firing mechanism and a charge for the torpedo readily removable and insertible, so that these parts can be kept separate from the torpedoes while the latter are carried in the planting or mooring vessel and need only be applied to the torpedo when the latter is about to be moored.

With these objects in view, and others as will appear as the description proceeds, the invention comprises various novel features of construction and arrangement of parts which will be more fully described herein-after and set forth with particularity in the claims appended hereto.

In the accompanying drawings, which illustrate one embodiment of the invention,

and wherein similar reference characters are employed to designate corresponding parts throughout the several views, Figure 1 is a central vertical section of the torpedo with the firing mechanism in elevation. Fig. 2 is an enlarged sectional view of the firing mechanism showing the firing pin or hammer set or in cocked position; Fig. 3 is a top plan view of the firing mechanism with the inertia or resistance element removed; and Fig. 4 is a horizontal section on the line 4—4 of Fig. 2.

Referring to the drawing, A designates the body of the torpedo, which may be spherical, cylindrical or any other shape which will acquire a rotative motion by being grazed by the hull of a vessel, and on the body A is a firing mechanism B which is controlled by an inertia or resistance device C. The torpedo or mine A is moored by means of an anchor cable 1 which passes through a guide pulley 2 at the bottom of the torpedo, and the upper end of the cable is fastened to a locking bolt operating means D which enables the inertia device C to be rendered operative as long as the torpedo is moored and tension is maintained on the anchor cable 1 by the buoyancy of the torpedo.

The firing mechanism B is mounted in a casing 3 fastened to the top of the torpedo A. The casing 3, which is rectangular in horizontal cross-section, contains a horizontal cylinder or guide 4 in which is slidably mounted a firing pin or hammer 5, said pin consisting of a piston 6 slidably engaging the cylinder 4, and a stem 7 slideable in an opening 8 formed in a cap or head 9 which closes the outer end of the firing pin cylinder 4. Between the piston 6 and cap 9 is a spring 10 which is under compression when the firing pin is in set position. The firing pin has a projection 11 which is normally in engagement with the arcuate flange 12 on a wheel 13 that rotates on a hollow boss or bearing 14 arranged on the cylinder 4. This wheel 13 is adapted to turn when the torpedo rotates, and eventually the flange 12 moves out of engagement with the projection 11 of the firing pin, thereby freeing the latter so that its spring 10 will cause the firing pin to strike the percussion cap 15, thereby firing the detonator 15^a, that in turn ignites the fuse or preliminary explosive device 16, such device 16 and cap 15 being a unitary element which is insertible

in an opening 17 in one side of the firing mechanism casing 3. The device 16 has a removable cover 18 for permitting the preliminary charge to be supplied, and entrance of water is prevented by a gasket 19. A gasket 20 is also provided between the flange 21 and the ring 22 into which the device 16 is threaded. When the explosion takes place in the device 16, the detonator 23 in the torpedo is exploded by influence, which in turn fires the charge in the container 24, and thereby the ignition of the main charge 25 is effected. This main charge surrounds the container 24, which latter extends diametrically of the torpedo and is removable upon the removal of a cap or plug 26. The container 24 and charge therein as well as the device 16 are inserted just prior to the torpedo being moored, so that during transportation in a vessel the torpedoes are absolutely harmless. The detonators 15^a and 23 consist of fulminate of mercury, the device 16 contains dry gun cotton, and the devices 24 and 25 contain wet gun cotton.

The rotation of the firing pin controlling wheel or element 13 is brought about by the inertia or resistance device C, which is so designed that it tends to remain stationary while the torpedo as a whole rotates. This device C may be constructed in a variety of ways and suitably located with respect to the torpedo body. In the present instance it is in the form of an approximately tangentially extending arm or lever 27 which has on its outer end a tail or vane 28, while its inner end is formed into a head 29 which has a non-circular opening 30 to fit the non-circular upper extremity 31 of a vertical shaft 32 which extends into the casing 3 through a stuffing box 33. On the inner portion of this shaft is a pinion 34 which meshes with a large gear wheel 35 that is fastened to a shaft 36 which in turn carries a small pinion 37, the latter meshing with gear teeth 38 on the wheel 13. By reason of this construction the shaft 32 remains substantially stationary because the resistance device C prevents rotation while the torpedo A rotates, and this relative rotation causes the wheel 13 to rotate and release the firing pin when the torpedo has made a predetermined number of revolutions. To permit access to the gear chamber the top 40 of the casing 3 is removable, and between the top 40 and the flange 41 of the casing 3 is a packing or gasket 42 which is compressed by the tightening of the bolts 43 that hold the top 40 in place. The stuffing box 33 is carried by the top 40, as is also an internal bearing 44 for the upper end of the shaft 36, there being a bearing 45 in the casing for the lower end of the shaft 36. In order to prevent breakage of the resistance device C the shank thereof or that portion between the tail 28 and head 29 is or may be a coiled spring of

suitable rigidity. To restrain the resistance device C against movement by the current of the water or the surf an easily broken constraining device, such as a wire 46, is connected with the shank 27 of the device C and with a suitable part of the torpedo, such as the ring 47. This element 46 will break when the body of the torpedo rotates by coming into contact with a vessel, since the resistance offered by the device C is greater than the tensile strength of the wire 46.

Upon withdrawing the torpedo from the water it is desirable that the resistance device C be locked against movement, and for this purpose a locking bolt 48 is provided to engage in a recess 49 in the flange 50^a of the head 29 of the device C, the bolt being movably mounted on a fixed part of the torpedo, as for instance, the bolt 48 is carried by a pivot 51 on the casing 50 of the bolt operating device D. This device D comprises a piston or plunger 52 slidable in the casing 50 and having rising therefrom a pair of lugs or ears 53 between which the intermediate portion of the swinging bolt or catch 48 is disposed, there being a pin 54 pivotally connecting the catch 48 with the lugs 53. The slidable element 52 is formed with a hollow stem 55 which receives the enlargement 56 on the end of the anchor cable 1, and into this hollow stem is screwed a plug 57 which has an opening 58 for receiving the anchor cable 1. The casing 50 has a cylindrical guide 59 in which the stem 55 has a sliding fit, and surrounding the guide is a spring 60 which has its upper end engaging the piston 52 and its lower end engaging the web 61 that connects the guide 59 with the casing 50. By this arrangement the spring 60 is housed in a practically water tight chamber. The pull on the anchor cable, due to the buoyancy of the torpedo, holds the piston 52 downwardly against the tension of the spring 60, and consequently the locking bolt or catch 48 is disengaged from the head 29 of the resistance device C, but as soon as the draft on the anchor cable is removed, as when the torpedo is being withdrawn from the water, the spring 60 comes into play and raises the piston 52, which in turn throws the free end of the locking bolt 48 into engagement with the head of the device C. If desired, the said head may have other recesses 62 in addition to the recess 49 as shown in Fig. 3, so that the locking bolt can have a locking engagement with the device C should not the recess 49 be in registry with the locking bolt. As shown in Fig. 2, there is a guide pulley 63 in the bottom of the casing 50 for the anchor cable 1, such anchor cable passing into the casing 50 through an opening 64. It is to be understood that in the mooring of the torpedo the locking bolt 48 will be automatically retracted or released.

From the foregoing description taken in connection with the accompanying drawings, the advantages of the construction and method of operation and of the apparatus shown will be readily understood by those skilled in the art to which the invention appertains, and while I have described the principle of operation, together with the apparatus which I now consider to be the best embodiment thereof, I desire to have it understood that the apparatus shown is merely illustrative, and that such changes may be made when desired as are within the scope of the appended claims.

Having thus described my invention, I claim as new and desire to secure by Letters Patent:

1. The combination with a torpedo adapted to be rotated by contact with a vessel, of a resistance device carried by the torpedo, said resistance device being held in its position by the resistance of the water during the rotation of the torpedo, and means actuated by the movement of the torpedo with respect to the resistance element for exploding the torpedo.

2. The combination with a torpedo adapted to be rotated by contact with a vessel, of a resistance device carried by the torpedo, said resistance device being held in its position by the resistance of the water during the rotation of the torpedo, means actuated by the movement of the torpedo with respect to the resistance element for exploding the torpedo, said means comprising a normally locked firing pin, and means for releasing the firing pin.

3. The combination of a torpedo of the class described, a firing mechanism therefor, a resistance device tending to remain in its initial position while the torpedo moves by contact with a vessel, and means controlled by the relative movement of the said device and torpedo for actuating the firing mechanism.

4. The combination of a torpedo, a firing mechanism therefor, a resistance device connected with the torpedo and adapted to remain substantially stationary while the torpedo moves by contact with a vessel, means for permitting the firing mechanism to operate after a predetermined relative movement of the torpedo and device, a locking means for the said device, and an anchor element 55 for the torpedo operatively connected with the said means to release the latter from the device when the torpedo is moored.

5. The combination of a torpedo adapted to be moored in a body of water and to be rotated by contact with a vessel, firing mechanism for exploding the torpedo, said firing mechanism including a firing pin, a resistance element carried by the torpedo and shaped to oppose movement through the water during the rotation of the torpedo,

and a gearing between the resistance element and the firing pin and adapted to be operated by the rotative movement of the torpedo with respect to the resistance element.

6. The combination of a torpedo, a resistance element, a connection between the element and torpedo for permitting the latter to turn by contact with a vessel while the element remains substantially stationary, a firing mechanism including a hammer, means for moving the hammer on its firing stroke, and a device normally holding the hammer set and adapted to be released therefrom by the relative movement of the said resistance device and torpedo.

7. The combination of a torpedo, a firing mechanism therefor including a hammer, an anchoring means for permitting the torpedo to rotate on an approximately vertical axis, a resistance device extending transversely to the axis of rotation of the torpedo, a connection between the resistance device and torpedo for permitting the latter to turn while the resistance device remains substantially stationary, a catch for holding the hammer in set position, and a gearing between the said resistance device and torpedo for causing the catch to move out of engagement with the hammer when the torpedo has revolved to a predetermined extent.

8. The combination of a torpedo, a firing mechanism, a casing on the torpedo inclosing said mechanism, said mechanism including a hammer, a shaft extending into the casing, a catch operatively connected with the shaft and arranged to hold the hammer in set position, and a resistance device connected with the shaft and having a blade whereby the said device tends to remain stationary while the torpedo is rotated.

9. The combination of a torpedo, a firing mechanism including a hammer, a casing inclosing the firing mechanism, a shaft extending into the casing, a stuffing box around the shaft, a catch for holding the hammer in set position, a train of gears operatively connected with the shaft and on one of which gears the catch is mounted, and a resistance device disposed externally of the torpedo and casing and connected with the shaft for holding the same relatively stationary while the torpedo turns, whereby the said hammer is finally released.

10. The combination of a torpedo, a firing mechanism, a resistance device opposed to movement through the water with the torpedo as the latter is turned by contact with the vessel, a locking bolt carried by the torpedo and adapted to engage said device for holding the same against movement, an anchor element for the torpedo, and means between the anchor cable and said locking bolt for holding the latter retracted as long as the buoyancy of the cable maintains the anchor element taut and for throwing the lock-

ing bolt into engagement with the resistance device when the tension of the anchor cable is removed.

11. The combination of a torpedo, a resistance device pivotally connected therewith and opposed to movement through the water as the torpedo turns by contact with a vessel, a movable element on the torpedo, an anchor cable connected with the element, 5 a spring on the element and held under tension as long as there is a draft on the anchor cable by the buoyancy of the torpedo, and a locking bolt connected with the element and held normally released from the anchor device and adapted to move into engagement 10 with the device when the tension on the anchor cable is removed.

12. The combination of a torpedo moored to revolve by contact with a vessel, a device 20 tending to remain stationary while the torpedo revolves, a firing mechanism for the torpedo controlled by the said device, and a breakable element between the said device and torpedo for restraining the latter

against relative movement of the torpedo 25 and device by water currents and the like.

13. The combination of a torpedo moored to rotate by contact with a moving vessel, a device on the torpedo tending to remain stationary as the torpedo rotates, and a firing 30 mechanism controlled by said device, said device comprising a flexible arm and a blade carried thereby.

14. The combination of a torpedo, a firing mechanism including a preliminary charge 35 and a hammer for igniting the same, a firing charge in the torpedo ignited by the preliminary charge, said charges being removable intact from the said mechanism and torpedo respectively, and a resistance device for controlling said firing mechanism. 40

In testimony whereof I have signed my name to this specification in the presence of two subscribing witnesses.
